UNITED STATES PATENT OFFICE.

BENJAMIN G. STAUFFER, OF HARRISBURG, PENNSYLVANIA.

DESIGN FOR AN ELECTROTHERAPEUTIC DEVICE.

SPECIFICATION forming part of Design No. 34,964, dated August 20, 1901.

Application filed June 3, 1901. Serial No. 63,039. Term of patent 7 years.

To all whom it may concern:

Be it known that I, BENJAMIN G. STAUFFER, a citizen of the United States, residing at Harrisburg, in the county of Dauphin and State of Pennsylvania, have invented and produced a new and original Design for an Electrotherapeutic Device, of which the following is a specification, reference being had to the accompanying drawing, forming a part thereof, which represents a perspective view of an electrotherapeutic device embodying the features of my design.

The design presents the circular marginal contour *a*, from which run the radially-disposed slits *b*.

It will be noticed that the general outline of the device is circular, the circle being broken at its quarters by the comparatively narrow radially-extended slots, whose sides extend on straight lines to their outer ends, where they intersect the circular margin of the device, and the opposite sides of the sev-

eral slots are parallel with each other, the line or direction of each slot being at a right angle to that of the adjacent slot and the general direction of each slot being radial and the sides of each slot being parallel with the radial direction of the slot, the whole presenting the appearance of a circular disk which is broken at its quarters by the relatively narrow radial slots.

Having described my invention, what I claim as new, and desire to secure by Letters Patent, is—

The design for an electrotherapeutic device, 35 as herein shown and described.

In testimony whereof I have signed my name to this specification in the presence of two subscribing witnesses.

BENJAMIN G. STAUFFER.
